UNITED STATES PATENT OFFICE.

HENRY C. WILLIAMSON, OF BUNTYN, TENNESSEE.

VENDING MACHINE.

Application filed May 26, 1927. Serial No. 194,488.

This invention relates to vending machines and particularly to vending machines designed for the purpose of vending school supplies such as tablets, pencils, erasers, and 5 the like.

The general object of the invention is to provide a machine of this character which is very simple in construction, which is positive in its operation, which is not likely to 10 get out of order, and which is so constructed as to positively prevent the chance of vending more than one article at a time, and which is permitted to be operated upon the deposit to a suitable coin or token.

15 A further object is to provide a machine of this character including article pushing devices which, when the handle of the machine is operated, move upward behind the article to be vended, shift the article out of 20 the delivery slot in the casing of the machine, then move rearward behind the next article and into position to be shifted upward behind the next article upon the deposit of another coin.

25 A still further object is to provide means including the article pushing mechanism which will prevent any reverse movement of the handle after an initial movement has been made until the handle has been completely moved in one direction.

Other objects will appear in the course of the following description.

My invention is illustrated in the accompanying drawings wherein:

35 Figure 1 is a side elevation of a vending machine constructed in accordance with my invention;

Fig. 2 is a perspective view of the handle lock;

40 Fig. 3 is a vertical section from front to rear through the machine;

Fig. 4 is a horizontal section looking down upon delivery plate;

Fig. 5 is a fragmentary sectional perspective view of a portion of the delivery plate;

Fig. 6 is a perspective view of the connected pushers.

Referring to these drawings 10 designates a casing which may have a width equal to 50 the article to be vended as, for instance, equal to the width of a tablet, and may have any desired height so as to provide a magazine 11, disposed above the actuating mechanism, the bottom of this magazine being formed 55 by the longitudinally extending, horizontally

disposed plate 12. The forward end of this plate extends out through the front wall 13 of the casing so as to form a delivery tray upon which the article to be vended is pushed for delivery. The rear wall of the 60 casing may be closed or simply inwardly flanged and means are, of course, provided whereby the articles such as tablets or the like, may be disposed in superposed relation within the casing.

65 The plate 12, as illustrated in Figure 4, is formed with two longitudinally extending slots 14, these slots being spaced from each other, and spaced from the side edges of this plate 12, and these slots at their rear ends are laterally enlarged as at 15, and at their forward ends laterally enlarged as at 16. The enlargements 15 are longer than the enlargements 16 and the rear ends 17 of the webs of metal which extends between the 70 enlargements 15 and 16 are downwardly deflected, as shown in Figure 3. Each of these webs of metal 18 is formed with inwardly extending slots 19, the forward wall of each slot being slightly depressed so that 75 these slots in effect constitute ratchet teeth with which the pusher coacts to prevent reverse movement of the actuating mechanism after an initial movement has been made. The plate 12 at its rear end is downwardly 80 flanged as at 20, and rearward of the front wall 13 is provided with the downwardly extending flange 21.

85 Carried by the flanges are the two longitudinally extending guide rods 22. Mounted upon these guide rods for sliding movement is the slide or carriage 23 having downwardly extending flanges 24 perforated for the passage of the guide rods. This carriage on its under side has the downwardly projecting ears 25 and pivoted to these ears is the longitudinally extending connecting rod 26, the forward end of which is connected to an arm 27 mounted upon a transverse actuating shaft 28.

100 The front wall of the casing 10 below the plate 12 is slotted at 29 for the passage of the arm 27. The shaft 28 is supported upon the ears or supporting brackets 30 extending out from the casing and mounted upon the shaft 28 is the handle 31 whereby the vending machine may be actuated.

105 Pivotedly mounted upon the carriage 23 are a pair of pushers 32. Each of these pushers consists of a short arm mounted 110

upon a common shaft 33 and the metal at the top and forward end of each arm is angularly bent laterally, as at 34, and preferably bent over upon itself to form a relatively thick head 35 adapted to engage behind a tablet or other article to be vended. The rear edge of the portion 34 is thinned down and bent downward slightly as at 37, to constitute a tooth which will engage with the ratchet notches or slots 19 as the carriage moves forward beneath the plate 12. The two pushers 32 are connected to each other by a transverse web 38 which is depressed below the upper faces of the pushers and a transverse rod 39 projects out from one of the pushers. It will be understood, of course, that each of these pushers 32 has a width equal to the width of the enlargements 15 and 16 of the slots 14. A spring 40 acts to urge both of said pushers downward into parallel relation to the carriage 23.

For the purpose of raising the pushers so that upon a forward movement they may be engaged with the downwardly depressed lip 17 of each web 18, I provide a lever 41 pivotally mounted at 42, upon the side wall of the casing, this lever extending rearward beyond the edge of the side wall of the casing and then being deflected inward and extending longitudinally beneath the pin 39. The rear end of this lever is connected to the contractile spring 43 which urges the rear end of the lever upward. The forward end of the lever is pivotally connected by a link 44 to a lever 45 pivoted at 46 upon the side wall of the casing and extending forward beyond the side wall.

Mounted upon the shaft 28 is a locking member 47 which is provided with a cam 40 constituted by a pin 48 which extends beneath the forward end of the lever 45 and when the shaft 28 is shifted in the direction of the arrow in Figure 1 this pin 48 rides upward beneath the lever 45, raising the forward end of the lever 41. This causes the rear end of the lever to be depressed. Upon the insertion of a coin, it is necessary that the forward end of the lever be depressed and the rear end raised to raise the pushers out of the enlargements 15 of slots 14 and against the action of the spring 40. To this end I provide a keeper 49 mounted upon the lever 41 and provide a pivoted latch 50 mounted adjacent the keeper and which normally engages beneath the bill 51 of the keeper. This latch has the form of a bell crank lever and is pivoted at 52 and the forward end of the latch is pivoted to a connecting rod 53, which in turn is connected to the coin actuated mechanism which may be of any desired character.

When a coin has been deposited it causes the depression of the connecting rod 53 and this retracts the latch 50 from beneath the bill 51. The spring 43 then acts to raise

the rear end of the lever 41 and this lever, acting upon the pin 39, lifts both of the pushers 32 into an upwardly and forwardly inclined position. If then the lever 31 be shifted forward, the arm 27 will, through the connecting rod 26, act to shift the carriage 23 forward. The pushers 32 will thus ride over the top of the webs 18 of the plate 12 and push the article to be vended out through the delivery slot. When the pushers reach the forward enlargements 16 the spring 40 will cause the depression of the pushers, which will drop downward into the enlargements 16 and into parallel relation to the carriage 23, and upon a backward movement of the carriage, caused by the contractile spring 54, which is attached to arm 27 and to any suitable portion of the casing 10, the carriage will move backward to its initial position. When the carriage reaches its initial position, the pushers will still be lowered and will remain lowered and in inoperative position until a coin is again deposited, so that even though the locking mechanism for the handle, which will be later described, is not released, the actuation of the handle would have no effect in delivering any goods through the delivery slot. As the pushers 32 move forward over the webs 18, the pushers will successively pass the notches 19 and as before explained, these notches act as ratchet teeth, preventing any rearward movement of the pushers until the pushers have dropped through the enlargements 16. Thus it will not be possible for a person to partially actuate the pushers to slightly project an article, pull the article out of the delivery slot, return the pushers to their initial position, and secure a new article without the deposit of a second coin.

For the purpose of locking the handle from any actuation until a coin is deposited, I provide the locking member 47. This, as before stated, extends upward from and is mounted upon the shaft 28 and is provided at its upper end with the tooth 55.

Pivotaly mounted upon the wall of the casing 10 is a handle latch 56 in the form of a lever pivoted at 57. This is angular in cross section and the top flange of the lever is extended forward out through an opening 58 in the casing wall and is widened and formed with a longitudinally extending slot 59. The forward end of this widened portion of the lever is upwardly turned as at 60. The rear end of the lever carries a depending ear 61 which extends out through a slot 62 in the casing wall and is connected to the coiled contractile spring 63. A link 64 is pivoted to the lever 41 and the lower end of this link is slotted as at 65, and a pin 66 extends through this slot into the ear 61. The spring 63 acts to urge the forward end of the locking lever 56 downward so as to hold this forward end in en-

gagement with the tooth 55. When the coin is deposited and the latch 50 withdrawn from engagement with the tooth 51, the forward end of the lever 41 drops and 5 through the link 65, forces the rear end of locking lever 56 downward, raising this forward end free of the tooth 55, which permits the handle to be shifted and permits, of course, the actuation of the vending 10 machine. Upon the return of the handle 31 to its normal position, the curved face of the handle lock 47 rides against the curved face 60 of the latch 56 and lifts the same until the tooth 55 has passed into the slot 15 59, and then the spring 63 again causes the latch to engage the tooth 55 and the handle is locked.

The operation of the mechanism will be clear from what has gone before, but to summarize the same it may be said that upon the deposit of a coin, the latch 50 is withdrawn from detent 51, the rear end of lever 41 is raised by spring 43, which lifts the pushers and at the same time lifts the forward end 25 of latch 56. The handle is then pulled forward which causes the pushers to ride forward over the bottom of the magazine, shifting the article out through the delivery slot.

When the handle has been brought forward 30 to its full extent, the pushers drop into the extension slots 16 and the handle may then be permitted to return to its normal position under the action of spring 54, which causes the return of the carriage and the 35 pushers to their normal positions beneath the enlarged slots 15 and the parts are ready for a new actuation.

Of course, it will be understood that the casing 10 constitutes a supporting frame 40 which is enclosed within an outer casing or cabinet so that all of the mechanism except the handle 31 and the knobs for the coin controlled mechanism is enclosed. This outer casing, of course, has a slot through 45 which the articles to be vended may be discharged.

It is intended that a number of these machines designed to vend supplies for students of public schools and in other places, 50 shall be disposed upon a common storage cabinet. Thus, each school will have a "supply table" as it is called, from which articles may be secured upon the deposit of a coin. These "supply tables" have been 55 instituted in a number of schools in different cities through the efforts of the parent-teachers association of the schools and my vending machines are designed to supply means whereby these articles may be vend- 60 ed without the necessity of employing a sales person to sell the supplies or relying upon the honor of the pupils.

Any suitable coin actuated mechanism 65 may be used for releasing the locking latch on this machine, though preferably I use

the coin actuated mechanism disclosed in my co-pending application before referred to.

While the casings of the vending machines may be constructed of different widths so as to accommodate articles having different widths or lengths, yet preferably the casings will all have the same width but where the article is narrower than the maximum width of the casings, fillers will be placed on the inside of the casing or shell to fill up 70 the extra space and cause the articles to stack up uniformly. Preferably the machines will be designed to hold tablets 8 1/2" wide. It will be understood that while I have described this machine as being particularly designed for vending tablets, that it may be used for vending other articles such as pencils, pen holders, rubber erasers, etc.

It will be understood that the mechanism illustrated in the drawings is designed to 85 be encased within an outer casing or cabinet shown in dotted lines and designated A so that all the operating parts of the vending machine except the handle are concealed within the outer casing. Obviously the dimensions and form of the case will depend 90 upon the purpose for which the vending machine is used.

I claim:

1. In a vending machine, a fixed article 95 supporting plate constituting the bottom of a magazine, a carriage travelling beneath said plate, an article pusher movably mounted on the carriage normally disposed beneath the plate, manually controllable means acting to shift the pusher above the plate and into engagement with the article, manually actuatable means for shifting the carriage longitudinally of and upon the plate as a support to eject the article, and means 100 causing the pusher to shift to its normal position entirely beneath the plate when the pusher has reached the end of its stroke.

2. In a vending machine, a fixed article supporting plate constituting the bottom of 110 a magazine, a carriage reciprocating beneath said plate, an article pusher movably mounted on the carriage and normally urged to a position beneath the plate, manually controllable means actuatable to shift the pusher above the plate when the pusher is at the rear end of its stroke to bring the pusher into engagement with an article, manually actuatable means for shifting the carriage longitudinally of and upon the plate as a support to eject the article, the plate being so 115 formed as to permit the pusher to shift to its normal position entirely beneath the plate when the pusher has reached the forward end of its stroke.

3. In a vending machine, a fixed article supporting plate constituting the bottom of a magazine, a carriage reciprocating beneath said plate, an article pusher movably mounted on the carriage normally urged to a pos- 130

- tion beneath the plate, manually controllable means actuatable to shift the pusher above the plate when the pusher is at the rear end of its stroke to bring the pusher into engagement with an article, manually actuatable means for shifting the carriage longitudinally of and upon the plate as a support to eject the article, the plate being so formed as to permit the pusher to shift to its normal position entirely beneath the plate when the pusher has reached the forward end of its stroke, and means preventing a return of the pusher to its retracted position until it has made a full ejecting stroke.
- 15 4. In a vending machine, a fixed article supporting plate constituting the bottom of a magazine, a carriage reciprocating beneath said plate, an article pusher pivotally mounted on the carriage and resiliently urged to a position beneath the plate, manually controllable means actuatable to shift the pusher above the plate and into engagement with the article, an actuating handle operatively connected to the carriage whereby the carriage may be shifted forward, the pusher operating over and being supported by the plate upon the forward movement of the pusher with the carriage, and means preventing a return of the pusher to its retracted position until it has made a full ejecting stroke, the plate being so formed as to permit the pusher to drop to its normal position entirely beneath the plate when the pusher has reached the forward end of its stroke.
- 30 5. In a vending machine, an article supporting plate constituting the bottom of a magazine, a carriage travelling beneath said plate, an article pusher pivoted upon the carriage and yieldingly urged to a position beneath the plate, an actuating handle operatively connected to the carriage to shift it, manually releasable means for latching the handle from actuation, and means actuated by said last named means acting to shift the pusher to a position above the plate and into engagement with the article, the plate being so formed at its forward end as to permit the pusher to drop into a position beneath the plate when a full forward stroke has been made.
- 35 6. In a vending machine, an article supporting plate constituting the bottom of a magazine, a carriage travelling beneath said plate, an article pusher pivotally mounted on the carriage and yieldingly urged to a position beneath the plate, the plate being longitudinally slotted to permit the projecting of the article pusher through the plate, the slot being widened at its opposite ends, an actuating handle operatively connected to the carriage, a lever having its rear end operatively engaged with the pusher when the later is in its retracted position, means urging the rear end of said lever upward to thereby raise the pusher to a position above

the plate, and a manually releasable latch normally holding the rear end of the lever depressed.

7. In a vending machine, an article supporting plate constituting the bottom of a magazine, a carriage travelling beneath said plate, an article pusher pivotally mounted on the carriage and yieldingly urged to a position beneath the plate, the plate being longitudinally slotted to permit the projecting of the article pusher through the plate, the slot being widened at its opposite ends, an actuating handle operatively connected to the carriage, a lever having its rear end operatively engaged with the pusher when the later is in its retracted position, means urging the rear end of said lever upward to thereby raise the pusher to a position above the plate, a manually releasable latch normally holding the rear end of the lever depressed, a latch operatively engaging the handle and normally preventing actuation thereof, and means connecting the lever to said last named latch to cause a release of the last named latch when the first named latch is released and the lever shifted under the action of its spring.

8. In a vending machine, an article supporting plate, constituting the bottom of a magazine and formed with two longitudinally extending slots, the slots being laterally widened at their ends, a carriage travelling beneath said plate, a pair of article pushers connected to each other for unitary movement and pivotally mounted upon the carriage, means urging the article pushers downward to the position beneath said plate, each article pusher having a shank adapted to travel through the slot, and a head larger than the slot but adapted to pass through the enlarged ends of the slot, an actuating handle operatively connected to the carriage to cause the coincident movement of the carriage when the handle is shifted, manually controlled means for lifting both of said pushers to a position above the face of the plate through the rearward enlargements of the slots, and means preventing reverse movement of the carriage and of the lever until the carriage has made a full stroke forward and the pushers are dropped through the forward enlargements of the slots.

9. In a vending machine, an article supporting plate constituting the bottom of a magazine, a carriage travelling beneath said plate, an article pusher on the carriage yieldingly urged to a position beneath the plate but movable into position above the plate, an actuating handle operatively connected to the carriage to shift it, a spring urging the carriage rearward, a lever having its rear end disposed beneath the rear end of the plate and engaging beneath a portion of the pusher, a spring urging the rear end of the lever upward to thus raise the pusher

into a position above the plate, a keeper carried by the lever, a shiftable latch normally engaging said keeper to hold the forward end of the lever raised and its rear end depressed, manually actuatable means for releasing said latch, a handle latch operatively engaging the handle to prevent its actuation and operatively connected to said lever and lifted when the forward end of the lever is depressed, and means carried by the handle operatively engaging the forward end of the lever to lift it as the handle is moved forward, the upward movement of the lever permitting the first named latch to engage beneath the keeper.

10. In a vending machine, a supporting frame, an article pusher mounted upon the frame for longitudinal movement to eject an article, an actuating lever operatively connected to the frame, an arm associated and movable with the actuating lever, a latch normally engaging said arm and preventing the actuating movement of the lever, manually operable means for releasing said latch 25 to permit the forward movement of the lever and arm, and means carried by the arm for returning the latch to its operative position, said latch yieldingly shifting to permit the re-engagement of the latch with the arm 30 upon the return of the operating lever to its normal position.

11. In a vending machine, a supporting frame, an article ejecting means mounted in the frame, an actuating lever operatively connected to the ejecting means and actuating the same upon a movement of the lever in one direction from a normal position, a latch holding the lever from actuation and yieldingly urged to a latching position, manually controllable means for releasing said latch to permit the movement of the actuating lever in one direction, and means carried by the actuating lever acting to return the latch to its engaging position when the lever 45 is actuated.

12. In a vending machine, a supporting frame, article ejecting means, an actuating handle operatively connected to the ejecting means, a latch pivoted upon the frame and

operatively engaging the actuating handle 50 when the handle is in its normal position, a lever mounted upon the frame, means urging the forward end of the lever downward, the forward end of the lever being operatively connected to the rear end of the latch, 55 a manually releasable latch normally holding the forward end of the lever raised, and the latching end of the latch depressed in operative engagement with the handle, and means actuated by the forward movement of 60 the handle acting to lift the forward end of the lever and depress the handle engaging end of the latch as the lever is moved forward, the lifting of the forward end of the lever acting to operatively engage it with 65 the manually releasable latch.

13. In a vending machine, article ejecting means, a rock shaft operatively connected to the ejecting means to actuate the same, a handle upon the rock shaft, a latching arm 70 carried by the rock shaft and moving with the handle, a latch pivotally mounted upon the supporting frame and having its forward end formed for engagement with said arm and acting to prevent the forward 75 movement of the handle, a lever pivoted upon the frame and having one end operatively connected to the rear end of the latch, a spring engaging the opposite end of the lever to urge it upward, a keeper carried by 80 the latch engaging end of the lever, a second latch engaging with the keeper and normally holding the keeper raised and the forward end of the latch depressed, a pivoted, manually releasable latch mounted 85 upon the frame and normally engaging with said keeper, manually controlled means for releasing the last named latch, a second lever mounted upon the frame and operatively connected to the first lever to move therewith, and a cam carried by the rock shaft 90 rearward of the arm and engaging the second named lever to lift the same when the actuating handle is moved forward to thereby return the lever to its initial position. 95

In testimony whereof I hereunto affix my signature.

HENRY C. WILLIAMSON.
